ATTORNEY.

UNITED STATES PATENT OFFICE.

ERNEST JAMES WILLIS, OF NEW YORK, N. Y.

DESIGN FOR A BICYCLE-CRANK.

SPECIFICATION forming part of Design No. 21,059, dated September 22, 1891.

Application filed August 20, 1891. Serial No. 403,235. Term of patent 7 years.

To all whom it may concern:

Be it known that I, ERNEST JAMES WILLIS, of the city, county, and State of New York, have invented and produced a new and original Design for a Bicycle-Crank, of which the following is a specification, reference being had to the accompanying drawings, forming part thereof.

Figure 1 is a perspective view of the bicycle-crack, and Fig. 2 is a cross-section of the same, these two views being deemed necessary to fully illustrate my design.

The object of this design is to give to the crank a graceful and airy contour.

The leading feature of my design is in the

semi-oval web or body and the rib-like figure produced in relief upon the rounded or oval surface of the web. The web or body 10 of the crank is of a semi-oval cross-section, and the ends of the web merge in the flattened 20 apertured heads 12 and 13, and produced in relief centrally and longitudinally upon the web is a rib-like figure 14.

I claim—

The design for a bicycle-crack herein shown 25 and described.

ERNEST JAMES WILLIS.
